APPARATUS FOR DIVIDING MORE OR LESS THICK LIQUID OR PASTY MATERIALS—FOR INSTANCE, CHOCOLATE AND THE LIKE.

1,156,407.

Specification of Letters Patent.

Patented Oct. 12, 1915.

Application filed March 9, 1915. Serial No. 13,170.

To all whom it may concern:

Be it known that I, FRIEDRICH WILHELM KETTNER, a subject of the German Emperor, and residing at Altona, Prussia, Germany, have invented certain new and useful Improvements in Apparatus for Dividing More or Less Thick Liquid or Pasty Materials—for Instance, Chocolate and the like—of which the following is a specification.

- 10 The machines for dividing materials such as chocolate and the like known heretofore generally have a reciprocating piston working beneath a cylinder into which the material is fed by a closing valve.
- 15 Machines of this description are so constructed that either very thick fluid or pasty materials or that materials of a more liquid state can be treated. In the first instance outward motion of the piston is obtained by the pressure of the material itself and only the inward movement is brought about by the aid of some other motive power. For the outward movement the positive drive is not desirable on account of the liability of forming hollow spaces, which necessarily must be created when the piston moves at a greater speed, than the incoming material. When thin liquid material is used it is not possible to move the piston by pressing forward the material. The feed of the material is produced by the aid of a worm arranged within the feeding funnel, which worm cannot push the mass forward when it is thin. In such cases it is necessary to drive the piston positively in both directions, which can be done without inconvenience, since in using thin liquid materials there is no fear of creating hollow spaces.
- 40 From the above it will be understood, that it is impossible to treat thick liquid materials as well as thin liquid materials with one and the same machine as known heretofore without changing the construction of the machine to a considerable extent and this cannot be done without heavy costs.

According to the present invention means are provided for to allow the piston to be driven either positively or by the aid of the advancing material according to need. This object in view two horizontally movable pistons are used, which are operated by a common reciprocating member, which is releas-

ably connected with the pistons in such manner that each forward movement of the piston is produced by the said member while at the movement of this member in opposite direction the piston may be left to itself so as to carry out its outward movement by the action of the advancing material.

The new machine may be provided with a conveyer apron or endless band which carries the material (divided into portions) in dishes or trays away and which is operated by the driving means of the pistons. This has the advantage that the feeding movement of the conveyer apron can be held synchronously with the operation of the piston. Moreover an adjustability is provided for to change the stroke of the pistons, whereby also the feeding movement of the conveyer apron is changed correspondingly. The amount of the material divided off each time and the length of the trays should be in a certain proportion to one another.

In the drawings a machine is shown constructed according to the present invention by way of example.

Figure 1 is a sectional elevation of the machine and Fig. 2 an end view of the same. Figs. 3-6 represent details of the machine.

In the machine shown the material is fed into the funnel *a* within a lower prolongation of which a feeding worm *b* is arranged, which feeds the material to the rotatable valve *c*. Laterally to this valve there are the cylinders *f* within which work the pistons *e*. The piston rods *e'* are operated by driver arms *g*, which are mounted on a reciprocating sectional rod or spindle *i*. The two sections of the spindle are threaded at their inner ends left and right handed and are connected by a correspondingly left and right hand nut *h*. Parallel to the spindle *i* a driving shaft is journaled carrying two cams *l*, which are arranged in such complementary position, that when the shaft *k* rotates the sectional spindle *i* is moved longitudinally in one or the other direction by the cams operating the rollers *i'* arranged on the rod *i*. The distance between the rollers *i'* is such that on a revolution of the cams *l* there is a certain amount of lost motion of the rod *i* and therefore the pistons will always be brought close up to the valve *c* at an end position, while on

the return movement the corresponding arm g allows the piston e to stay behind, so that the latter can be moved outward merely by the advancing material. When the piston is moving toward the valve c the latter is in such a position that it directs the material downward thus allowing it to be pressed out through the nozzle c' .

Should it be desired to give the piston in both directions a positive movement it is only necessary to apply a suitable nut m to the piston rod e' as shown in Fig. 3^a, which firmly connects the arm g with the piston e . This connection is brought about when thin liquid mass is to be divided.

In order to change the distance between the two rollers i' and thereby alter the outward stroke of the pistons e the right and left handed nut h is provided with a worm-wheel n which is prevented from rotating on the nut by a sliding key and notch n' , at the same time allowing of a longitudinal motion of the nut, the worm-wheel being held between two flanges n'' fixed to the framing of the machine. The worm-wheel n can be rotated by a worm n^3 which is provided with a hand-wheel n^4 . The nut h is moreover provided with two flanges o , between which an eye o' loosely surrounds the spindle i . The eye o' is connected with a rack o'' which engages a tooth-wheel p . The latter is provided with a crank-disk q , which serves for operating a ratchet mechanism r , which in connection with the drum v operates the conveyer apron u . Preferably the disk q is provided with two crank-pins s and t which are connected with the pawls r' of the ratchet mechanism r and r^2 of the ratchet mechanism r^3 respectively by the two rods s' and t' . The two ratchet devices r , r' and r^2 , r^3 are equally constructed and are operated on every there and back motion of the nut h to move the conveyer apron u , on which the operator places the empty trays at one end, to an extent corresponding to the amount of material fed by one piston.

The crank-pins s and t may be arranged adjustably on the disk q . This adjustability is arrived at by two blocks w (Fig. 4), which are adapted to slide within a guide notch w' running diametrically across the disk q and which can be adjusted by a screw spindle x having right and left handed thread. This screw spindle is preferably provided with a hand-wheel y by the rotation of which the stroke of the ratchet devices can be changed at will.

The cam d for rotating the valve c is arranged on the shaft h in a plane central to the cams l . The cam d is adapted to operate a stud or pin d' on the arm d'' of the valve c . The cam notch, into which the pin d' projects has two oblique surfaces d^3 and two straight surfaces d^4 (Fig. 6) so

as to give the valve c a rest after a quick rotation during the movements of the pistons.

By rotating the hand-wheel n^4 evidently the stroke of the pistons e and therefore the feed of the material as well as the feed of the conveyer apron u is adjusted so that the desired synchronism is maintained at all events.

I claim:

1. Machine for dividing more or less liquid materials comprising two cylinders and two pistons working in the cylinders, a rotatable valve adapted to feed the said material to the cylinders, a reciprocating member releasably connected with the pistons, so as to positively operate the pistons in one direction and to allow the material to operate the pistons in the other direction.

2. Machine for dividing more or less liquid materials comprising two cylinders and two pistons working in the cylinders, a rotatable valve adapted to feed the said material to the cylinders, a reciprocating member releasably connected with the pistons and consisting of a sectional spindle, a left and right handed nut engaging the two sections of the spindle, a shaft and two cams mounted on the shaft and adapted to operate the reciprocating member.

3. Machine for dividing more or less liquid materials comprising two cylinders and two pistons working in the cylinders, a rotatable valve adapted to feed the said material to the cylinders, a reciprocating member releasably connected with the pistons, a shaft and two cams mounted on said shaft adapted to operate the reciprocating member, a cam disk mounted on the center of the said shaft and adapted to operate the rotatable valve.

4. Machine for dividing more or less liquid materials comprising two cylinders and two pistons working in the cylinders, a rotatable valve adapted to feed the said material to the cylinders, a reciprocating member releasably connected with the pistons, arms on the reciprocating member loosely engaging the pistons and adapted to be fastened to the said pistons.

5. Machine for dividing more or less liquid materials comprising two cylinders and two pistons working in the cylinders, a rotatable valve adapted to feed the said material to the cylinders, a reciprocating member releasably connected with the pistons and consisting of a sectional spindle, a left and right handed nut engaging the two sections of the spindle, a shaft and two cams mounted on the shaft and adapted to operate the reciprocating member, a hand operated gear adapted to adjust the right and left handed nut.

6. Machine for dividing more or less liquid materials comprising two cylinders and

two pistons working in the cylinders, a rotatable valve adapted to feed the said material to the cylinders, a reciprocating member releasably connected with the pistons, a ratchet mechanism and a conveyer apron operated by the ratchet mechanism.

7. Machine for dividing more or less liquid materials comprising two cylinders and two pistons working in the cylinders, a rotatable valve adapted to feed the said material to the cylinders, a reciprocating member releasably connected with the pistons, and consisting of a sectional spindle, a left and right handed nut engaging the two sections of the spindle, a ratchet mechanism and a conveyer apron operated by the ratchet mechanism, and disk arranged between the said nut and the ratchet mechanism, a rack-gear driven by the nut and adapted to oscillate the said disk.

8. Machine for dividing more or less liq-

uid materials comprising two cylinders and two pistons working in the cylinders, a rotatable valve adapted to feed the said material to the cylinders, a reciprocating member releasably connected with the pistons and consisting of a sectional spindle, a left and right handed nut engaging the two sections of the spindle, a ratchet mechanism and a conveyer apron operated by the ratchet mechanism, and disk arranged between the said nut and the ratchet mechanism, a rack-gear driven by the nut and adapted to oscillate the said disk, a crankpin arranged adjustably on the said disk and a connecting rod to connect the crankpin with the ratchet mechanism.
